(57) **CLAIM**

The ornamental design for a server cooling distribution unit, as shown and described.

DESCRIPTION

FIG. 1 is a front top right perspective view of my new design;

FIG. 2 is a rear top right perspective view thereof;

FIG. 3 is a rear elevation view thereof;

FIG. 4 is a front elevation view thereof; and

FIG. 5 is a right elevation view thereof; and,

FIG. 6 is a left elevation view thereof.

The bottom view is not seen during ordinary use and is no part of the claimed design. The broken lines in FIGS. 1-6 depict environmental structure, and the elements shown in broken lines form no part of the claimed design.

1 Claim, 5 Drawing Sheets
